UNITED STATES PATENT OFFICE.

DOUGLAS HAYNES CORBIN AND ARTHUR WILLIAM HARRIS, OF BIRMINGHAM,
ENGLAND, ASSIGNORS TO LIFE TARGETS LIMITED, OF LONDON, ENGLAND.

CINEMATOGRAPH TARGET APPARATUS.

1,125,661.

Specification of Letters Patent.

Patented Jan. 19, 1915.

Application filed May 16, 1914. Serial No. 839,004.

To all whom it may concern:

Be it known that we, DOUGLAS HAYNES CORBIN and ARTHUR WILLIAM HARRIS, subjects of the King of Great Britain, residing at 98 King's road, Erdington, Birmingham, in the county of Warwick, England, and Durley Dene, Jaffray Road, Erdington, Birmingham aforesaid, respectively, have invented a new and useful Improvement in Cinematograph Target Apparatus; and we do hereby declare the following to be a full, clear, and exact description of the same.

Our invention comprises improvements in cinematograph target apparatus of the kind which is described in the prior Patents Nos. 1027371, 1075894 and 1072298. In the prior patent specification No. 1075894 a means for arresting the movement of the cinematograph through the intermediary of sound waves propagated by the discharge of the rifle is shown, and the present invention embodies an improvement in or modification of the apparatus described in this said prior specification. In the said prior patent we have the motion arresting device illustrated as including a microphone, this specification also describing a modified form of the invention in which the microphone vibrates to make or break a circuit in circuit with a relay, the relay responding to variations of the current in the circuit including the microphone, but according to the present invention we provide an extremely simple mechanical device for breaking an electrical circuit such means embodying a pair of contacts normally engaging each other but located one on either side of a contact breaking member, attached to and actuated by the vibrations of the diaphragm.

Referring to the drawings:—Figure 1. is a part sectional plan of apparatus according to this invention. Fig. 2. is a perspective view of same.

In the prior patent specification No. 1075894 a relay 18 is described the contacts 20 of which are broken when the current passing through the windings around the polar extensions is varied under the influence of a microphone. According to the present invention a pair of flanking contact springs $a-a$ are employed which are intended to form part of the same circuit as the flanking contact springs 19 described in the prior specification these flanking contact

springs $a-a$ making contact with each other at a^1 . Between these contact springs a contact breaking member b having a hammer head b^1 is connected to and carried by a diaphragm c located in a sound collector d . This diaphragm is so tuned or constructed that when a shot is fired it will vibrate, the vibrations being imparted to the contact breaker which thus throws apart the flanking contact springs thereby breaking the circuit for the purpose of arresting the motion of the cinematograph, in the manner described in the prior specification No. 1075894.

The flanking contact springs $a-a$ are in circuit with the electromagnet e the cores of which are so wound as to retain the connection f in contact with the member g against the action of the spring h as long as current is passing in through said contacts; but as soon as the circuit is broken the armature i is pulled over, breaking the contact and de-energizing the relay j in similar manner to that described in the aforementioned prior specification.

What we claim then is:—

1. In cinematograph target apparatus, the combination of a cinematograph; a diaphragm responsive to sound waves; a contact member carried by said diaphragm; a pair of flanking contact springs located one on each side of said contact member normally maintaining a circuit but adapted to separate and open the circuit under the influence of vibrations set up by the diaphragm when a shot is fired; and means for arresting the movement of the cinematograph responsive to the separation of said flanking contact springs; for the purpose set forth.

2. In cinematograph target apparatus, the combination of a cinematograph; a diaphragm responsive to sound waves; a contact member carried by said diaphragm; a pair of flanking contact springs located one on each side of said contact member normally maintaining a circuit but adapted to separate and open the circuit under the influence of vibrations set up by the diaphragm when a shot is fired; means for arresting the movement of the cinematograph responsive to the separation of said flanking contact springs; a screen; and means responsive to the separation of said flanking contact springs for

actuating the screen for the purpose of obliterating shot holes; for the purpose set forth.

3. In cinematograph target apparatus,
5 the combination of a cinematograph; a dia-
phragm responsive to sound waves; a sound
collector of conical form containing said dia-
phragm; a contact member carried by said
diaphragm; a pair of flanking contact
10 springs located one on each side of said con-
tact member normally maintaining a circuit
but adapted to separate and open the circuit
under the influence of vibrations set up by
the diaphragm when a shot is fired; an elec-
15 tromagnet in circuit with said flanking con-
tact springs; and means for arresting the
movement of the cinematograph responsive
to the deenergizing of said electromagnet;
for the purpose set forth.
- 20 4. In cinematograph target apparatus, the
combination of a cinematograph; a dia-
phragm responsive to sound waves; a sound
collector of conical form containing said dia-
phragm; a contact member carried by
25 said diaphragm; a pair of flanking contact

springs located one on each side of said con-
tact member normally maintaining a circuit
but adapted to separate and open the circuit
under the influence of vibrations set up
by the diaphragm when a shot is fired; an 30
electromagnet in circuit with said flanking
contact springs; and means for arresting the
movement of the cinematograph responsive
to the deenergizing of said electromagnet; a
35 screen; and means responsive to the de-
energizing of said electromagnet for actu-
ating the screen so as to obliterate shot
holes; for the purpose set forth.

In testimony whereof, we have signed our
names to this specification in the presence of 40
two subscribing witnesses.
